[57] **ABSTRACT**

For joining wire of compound material having a core of aluminum and a casing of copper, the ends to be joined are shaped to form male and female parts, the male part is inserted in the female part, and a sleeve of explosive is applied around the joint and detonated so that the core and casing are joined in one operation by explosion welding.

**METHOD OF JOINING WIRE OR RODS OF
COMPOUND MATERIAL WITH ALUMINUM CORE
AND COPPER CASING**

BACKGROUND OF THE INVENTION

1. Field of the Invention

The invention relates to the joining of wire or rods of compound material with an aluminium core and a copper casing.

2. The Prior Art

Hydrostatic extrusion straight down to the desired final dimensions is uneconomical with very thin wire since the permissible cylinder pressure limits the extrusion ratio. The upper limit when extruding compound wire having an aluminium core and copper casing is less than 2,000, usually less than 1,000. The extrusion ratio possible decreases with increasing copper content. Thus, the extrusion ratio which can be achieved limits the weight of the billet. For high production and good economy in a press for hydrostatic extrusion the extruded wire must have a diameter of at least 5 mm. A diameter of 6 – 10 mm has been found to be extremely suitable for copper-aluminium wire. Lengths of 1,000 m and more can be obtained from one billet. The wire obtained can be machined by drawing to the desired dimension. When the extruded wire is drawn to a diameter of 0.4 mm, about 250,000 metres of wire are obtained from a single billet, which is more than enough for most purposes. However, lengths of 1,000 m are unsatisfactory as starting lengths for drawing in a drawing machine, since in principle drawing is a continuous method which requires enormous starting lengths if the production costs are to be kept low. A number of extruded lengths of wire must therefore be joined together in order to acquire lengths which can be economically drawn. It has been found extremely difficult to join compound wire having an aluminium core and copper casing, however, in such a way that it can be drawn. Most welding methods involve such alterations in the material at and around the joint that the wire breaks during the drawing process. One of the main reasons for this is that hard and brittle alloys are formed in the boundary layer between the casing and the core when the wire is heated. This alteration, which also causes hardness and greater brittleness at the joint, causes complications when drawing the wire to smaller dimensions. The drawing resistance alters when the joint passes a drawing plate and this may give rise to jerks so that the wire breaks. The brittle boundary layer may also be broken during the drawing so that the copper casing separates from the aluminium core and flakes off during the drawing process.

By joining the wire by means of pressure welding and removing the bulge the problem of hard compounds has been solved, but unfortunately a joint is obtained which has no casing. This type of joint also causes problems during drawing. Furthermore, the wire at the joint has other properties and a different appearance from the rest of the wire. In order to obtain a compound wire with uniform properties the joint has been provided with a new casing by joining a sleeve with the core and with the casings on either side of the joint by means of blast welding.

Compound wire having a core of aluminium and a casing of copper has also been joined by exposing the core at the joint and welding together the cores of the two wires, for example by means of electron-beam

welding, and then applying a casing over the joint by means of blast welding a sleeve or parts of the casing which was removed from the core and bent back so that the cores were accessible for welding.

5 By explosion welding is meant a welding method in which a material is influenced by a pressure wave and thus pressed against another material with such force that the two materials become metallically bonded.

SUMMARY OF THE INVENTION

The present invention relates to a method of joining wire of compound material having a core of aluminium and a casing of copper. According to the invention, the wire ends to be joined are shaped to form male and female parts, the male part is inserted in the female part, and a sleeve of explosive is applied around the joint and detonated so that the core and casing are joined in one operation by blast welding. The core angle of the female part may be greater than that of the male part, so that the wall of the female part deviates from the opposed wall of the male part. Likewise, the female part may be formed by longitudinal deformation of the wire followed by the formation of a conical recess in the deformed part.

25 **BRIEF DESCRIPTION OF THE DRAWINGS**

The invention will be further described with reference to the accompanying drawings;

FIG. 1 shows two wire ends shaped as a male and a 30 female part;

FIG. 2 the same wire ends brought together for joining and surrounded by a sleeve of explosive;

FIG. 3 a wire end clamped in a tool for axial upsetting of the wire end;

35 FIG. 4 the same wire end after having been upset under the influence of an axial force;

FIG. 5 the upset wire end shaped to a female part;

FIG. 5a an alternative design of the outermost part of the female part;

40 FIG. 6 another alternative design for the ends of the wire to be joined.

**DESCRIPTION OF THE PREFERRED
EMBODIMENTS**

45 In the drawings, 1a and 1b designate the core and 2a and 2b the casing in two wires or rods which are to be joined. The lefthand wire end is shaped as a male part with a conical point 3 with a cone angle α , the righthand wire end as a female part with a double conical recess 4 with a cone angle α in the core and a cone angle β in the casing. Since the recess is in the form of a double cone with the angle $\alpha > \beta$ the area A of the conical surface 5 will be greater than the area B of the conical surface 6. The casing 2a will therefore overlap

50 the casing 2b at the joint. The conical recess 4 is expanded so that a gap 7 is formed when the ends of the wires are fitted together, the size of this gap increasing with the distance from the centre of the wire. A sleeve 8 of explosive is fitted around the joint with an annular firing mechanism 9 connected to a release means, not shown, by means of a cable 10. It may be advisable to upset the ends of the wires axially so that their diameter increases as much as the diameter decreases due to the blast force during the explosion jointing. When the explosive sleeve is triggered the wire is subjected to a pressure wave moving to the left which forces the material 1a and 2a in the female part with considerable

55 60 65

force against the material $1b$ and $2b$ in the cone 3 in the male part. During the actual joining process the ends of the wire are fixed in relation to each other in a fixture, not shown. Any upset which may be formed at the joint by the casing $1a$ overlapping the casing $1b$ should be removed before the wire is drawn to smaller diameter in the drawing plates. When the recess 4 is expanded so that the cone angle is greater than the cone angle α of the male part in order to produce the gap 7 when the wire ends are fitted together, the outermost bevelled part of the copper casing may crack or be stretched differently at different parts of the circumference. An alternative process which avoids this drawback is shown in FIGS. 3 - 5. By upsetting the wire end which is to form the female part in a tool having two clamps 11 which fix the end of the wire axially, it can be given such a shape that the conical recess 4 can be given the desired cone angle without the previously mentioned expansion. The wire end a is inserted in the clamps 11 which provide a substantially conical opening. A tool, not shown, affects the wire end 12 with a force P so that the wire end a is axially upset and thus deformed to the shape determined by the tool clamps 11 , as shown in FIG. 4. The outer part 13 which has not been completely in contact with the tool clamps 11 must be removed. The wire end is cut along a line 14 . The conical recess can be shaped in various ways. The most simple design is shown in FIG. 5 where the recess 4 is completely conical. Another design is shown in FIG. 5a where the recess 4 has a smaller cone angle in the outer part, the copper casing $2a$, than in the inner part, the aluminium core $1a$. This means that the conical copper surface 5 in the female part is wider than the conical copper surface 6 of the male part. The widths are A and B , respectively. This means that the surface 5 will completely cover the surface 6 at the joint.

In the alternative method according to FIG. 6, the diameter of the wire end b is reduced before it is provided with a conical point. It is then possible to eliminate the expansion of the wire end a and in spite of this acquire a satisfactory connection between the casings $1b$ and $2b$. Furthermore, it has been found that the explosion gases damage the surface of the casing $2b$ at the side of the joint less in this embodiment than in the other embodiments. The gap 7 has substantially the same width along the entire length of the joint. The

male part is provided with a guide point 16 which positions it both radially and axially in the female part and determines the size of the gap 7 .

I claim:

- 5 1. Method of joining wire of compound material having a core of aluminium and a casing of copper, which comprises shaping two ends of said wire to be joined to form male and female parts, inserting the male part so far in the female part that the inner surface of the casing of the female part partly covers the unpointed, unshaped part of the casing of the male part, applying a sleeve of explosive around the joint and detonating it so that the core and casing of one wire end are joined to the core and casing of the other wire end in one operation by means of explosion welding.
- 10 2. Method according to claim 1, in which a gap is formed between the two wire ends when they are brought together.
- 15 3. Method according to claim 2, in which the shaping comprises shaping the male and female parts differently so that the gap formed between the two wire ends, which are brought together, increases towards the periphery of the wire.
- 20 4. Method according to claim 1, in which the shaping comprises shaping the male part with a conical point and the female part with a conical recess.
- 25 5. Method according to claim 4, in which the shaping comprises expanding the conical recess of the female part with a cone angle less acute than that of the male part.
- 30 6. Method according to claim 5, in which the shaping comprises shaping the female part with a conical recess which at the outer portion defined by the casing has a smaller cone angle than the inner portion.
- 35 7. Method according to claim 4, in which the shaping comprises upsetting the wire end which is to form the female part to conical form, and thereafter providing it with a conical recess.
- 40 8. Method according to claim 4, in which the shaping comprises machining the wire end which is to form the male part to a smaller diameter and providing it with a conical point.
- 45 9. Method according to claim 1, which comprises upsetting the wire ends axially to greater diameter before shaping them to male and female parts.
